(57) **CLAIM**

The ornamental design for a cap, as shown and described.

DESCRIPTION

FIG. 1 is a side perspective view of a cap showing my new design, in an environmental condition of use with an adaptor;

FIG. 2 is an enlarged bottom perspective view thereof, with the environmental subject matter removed for clarity of details;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

The broken lines are shown for the purpose of illustrating environmental subject matter and parts of the article that form no part of the claimed design.

1 Claim, 6 Drawing Sheets
